UNITED STATES PATENT OFFICE.

WILLIAM W. HUNTLEY, OF SILVER CREEK, AND FREDERICK D. WOLFROM,
OF ROCHESTER, NEW YORK, ASSIGNORS, BY MESNE ASSIGNMENTS, TO
THE HUNTLEY MANUFACTURING COMPANY, OF SILVER CREEK, NEW
YORK.

GRAIN-SCOURER.

SPECIFICATION forming part of Letters Patent No. 559,488, dated May 5, 1896.

Application filed February 5, 1894. Serial No. 499,118. (No model.)

To all whom it may concern:

Be it known that we, WILLIAM W. HUNTLEY, residing at Silver Creek, in the county of Chautauqua, and FREDERICK D. WOLFROM, residing at Rochester, in the county of Monroe, State of New York, citizens of the United States, have invented new and useful Improvements in Grain-Scourers, of which the following is a specification.

10 This invention relates to that class of scourers which consist, essentially, of a drum provided with scouring-teeth and revolving within a chamber having scouring-teeth.

The object of our invention is to produce a 15 scourer of this character which has a gentle scouring action and which is particularly suitable for scouring malt, seeds, and beans preparatory to cleaning the same by a separator employing an air-current.

20 In the accompanying drawings, Figure 1 is a longitudinal sectional elevation of a separator provided with our improved scourer. Fig. 2 is a fragmentary sectional elevation of the scourer, on an enlarged scale. Fig. 3 is a 25 horizontal section in line 33, Fig. 2. Fig. 4 is a fragmentary section of one of the scouring-teeth and its supporting-plate, on an enlarged scale.

Like letters of reference refer to like parts 30 in the several figures.

Although our improved scourer can be operated independently of any other machine, we have shown it in connection with a separator in which air-currents are employed, and 35 which consists, essentially, of a main frame A, shaking-shoe B, containing the sieves b, feed-box C, preliminary wind-trunk D and chess-hopper D', final wind-trunk E and chess-hopper E', and a fan F.

40 G represents a scouring-chamber formed in the upper portion of the feed-box and provided in its top with a feed-opening g. The vertical front and rear sides of the scouring-chamber are provided with metallic scouring-45 plates H H', and the bottom of the same is formed by two metal scouring-plates h h', which incline downwardly from the lower ends of the front and rear plates H H' toward the center of the feed-box. The rear plate h' is 50 rigidly secured with its upper end to the ver-

tical rear plate, while the front plate h is pivoted with its upper end to the vertical front plate H. The lower end of the pivoted plate h is separated from the lower end of the rigid plate h', forming an outlet-opening h², through 55 which the material passes from the scouring-chamber into the feed-box. The pivoted plate h can be adjusted toward and from the rigid plate h', for regulating the flow of the material, by means of a screw i, arranged in the front wall of the feed-box and bearing against the front side of the pivoted plate.

J represents scouring-teeth which are regularly disposed on the inner sides of the plates H H' h h' and in planes parallel with the longitudinal direction of the plates. Each of these teeth consist of a piece of round wire bent into a U-shaped staple. These staples are firmly secured with their arms to the scouring-plates, preferably by placing the 70 staples in a mold and casting the plates upon the ends of the staples.

K represents a scouring drum or cylinder arranged in the scouring-chamber lengthwise between the scouring-plates and mounted on a shaft k, journaled with its ends in bearings k', arranged in the end walls of the scouring-chamber.

M represents segmental scouring-plates secured to the outer side of the cylinder and 80 provided with scouring-teeth m, arranged to pass between the teeth of the scouring-plates. These teeth have the form of staples which are arranged in planes parallel with the axis of the scouring-cylinder, to correspond to the 85 position of the teeth on the scouring-plates H H' h h'. The teeth of the scouring-cylinder are secured to the segmental plates preferably by casting, in the same manner as the stationary scouring-teeth are secured to the 90 scouring-plates.

Upon rotating the scouring-cylinder when the scouring-chamber is filled with grain, seeds, or other material to be scoured the teeth of the cylinder pass through the grain 95 and also carry the same against the stationary teeth, thereby scouring the grain and removing the particles of dust and impurities therefrom. By constructing the scouring-teeth in the shape of staples, which are arranged in 100

planes lengthwise of the scouring-cylinder and scouring-plates, a larger scouring-surface is secured, because the grain is rubbed in passing through on the inner sides of both 5 legs of the staples and also around the outer sides thereof. This construction of a scouring-tooth also enables the same to readily pass through the material without carrying the latter around with the cylinder to any extent, 10 thereby enabling the machine to be run with less power.

By making the staples of round wire the scouring action of the same is very mild, which is particularly desirable for scouring 15 malt and other grains or seeds requiring gentle treatment. The grain is thoroughly scoured in the feed-box and also agitated therein by the scouring mechanism, whereby the feed is equalized and clogging is prevented. The grain is then immediately subjected to the action of the air-current in the 20

preliminary wind-trunk, and passes thence to the shaking-shoe, where it is screened, so that these several operations are performed in close connection in the same machine. 25

We claim as our invention—

The combination with a scouring-chamber and a toothed scouring-cylinder arranged therein, of toothed inclined plates forming the bottom of said scouring-chamber, one of 30 said plates being hinged and provided with an adjusting device whereby the opening between the two plates can be regulated, substantially as set forth.

Witness our hands this 27th day of Janu- 35 ary, 1894.

WILLIAM W. HUNTLEY.
FREDERICK D. WOLFROM.
